AUTOMATIC CHOKE VALVE

Russell F. Holmes and Lester M. Crabb, Flint,
Mich., assignors to General Motors Corpora-
tion, Detroit, Mich., a corporation of Delaware

Application March 25, 1935, Serial No. 12,999

9 Claims. (Cl. 123—119)

This invention relates to mechanisms for automatically regulating the position of the choke valve of the carburetor of an internal combustion engine when its temperature is below that at which it is designed to operate. The invention resides in the provision in such a mechanism of means for insuring that, as soon as the engine starts and begins to operate normally under its own power, the choke valve will be opened to the position at which the engine is supplied with a combustible mixture of the proper richness for cold idle operation and that the choke valve will not be closed beyond this position while the engine is idling normally.

For a better understanding of the nature and objects of this invention, reference is made to the following specification wherein there is described the embodiment thereof which is illustrated in the accompanying drawing.

In the accompanying drawing:

Figure 1 shows, mainly in elevation, mechanism in which our invention is embodied and associated parts of an internal combustion engine.

Figure 2 is a section through the mechanism taken on the line 2—2 of Figure 3.

Figure 3 is a section taken on the line 3—3 of Figure 2.

Figure 4 is a perspective view of two of the elements of the mechanism.

In the drawing, the reference 10 indicates a carburetor which is connected to the cylinders of an internal combustion engine by a manifold 11. In the carburetor 10, there is included a butterfly throttle valve 12 which is mounted on a shaft 13 to which an operating arm 14 is secured and a butterfly choke valve 15 which is mounted off-center on a shaft 16 so that the flow of air into the carburetor will tend to open it.

To the intake manifold 11 adjacent the carburetor 10, there is secured by means of screws 17 a hollow body 18 which is divided into upper and lower compartments by a partition 19. In the upper compartment, there is located a metal bellows 20 to whose open upper end there is secured a flange 21 whose outer edge is seated on the upper end of the body and clamped between it and the outer edge of an inverted cup-shaped cover 22 by screws 23. The lower end of the bellows 20 is closed by a head 24 to which there is secured a rod 25 which projects into the lower compartment of the body 18 through an opening in the partition 19. Expansion of the bellows 20 is limited by the partition 19 and contraction thereof is limited by a rod 26 which depends from the cover 22.

The interior of the bellows 20 communicates with the interior of the intake manifold 11 through a transverse bore 27 in the side wall of the cover 22 and a vertical bore 28 which extends through the upper wall of the intake manifold 11, the wall of the body 18 and into the cover 22. In the lower enlarged end of the portion of the bore 28 which is located in the body 18, there is screwed a plug-like element 29. In the upper surface of the plug-like element 29, there is provided a cylindrical recess 30 into which from the lower surface of the plug-like element there extends a relatively small bore 31. The recess 30 is surrounded by a cylindrical flange 32 to which there is secured a combined valve cage and guide 33 within which there is located a poppet valve 34 which is normally seated on the upper end of the flange by gravity and a light spring 35. Through a bore in the center of the valve 34, there extends a pin 36 whose diameter is slightly less than that of the bore and which is loosely connected to the upper end of the combined valve cage and guide 33 so that it may flutter during operation of the engine and dislodge any particles of foreign matter which may find their way into the small opening between it and the bore.

To the side of the body 18 which is nearest the exhaust manifold 37 of the engine, there is secured a bearing 38 whose inner end extends into the lower compartment of the body. On ears 30 which are formed on an intermediate portion of the bearing, there is seated a cup-shaped housing 39 whose open end is located adjacent the exhaust manifold 37 and into whose interior the outer end of the bearing 38 extends. The cup-shaped housing 39 is secured to the body 18 by the screws 40 which extend through the ears on the bearing 38 and secure the latter to the body.

In the bearing 38 there is journaled a hollow shaft 41 to whose inner end there is secured an arm 42. The outer end of the arm 42 is pivotally connected to the rod 25 which depends from the head of the bellows 20 and from an intermediate portion of the arm there projects a finger 43 which extends parallel to and beyond the inner end of the hollow shaft 41. A shaft 44 extends through and is journaled in the hollow shaft 41 and the wall of the housing 39 opposite that through which the bearing 38 extends. To the end of the shaft 44 which extends through the wall of the body 18 opposite that through which the bearing 38 extends, there is secured an arm 45 whose outer end is pivotally connected to one end of a rod 46. The opposite end of the rod 46 is pivotally connected to the outer end of an 55

arm 47 which is secured to the shaft 16 on which the choke valve 15 is mounted.

To the end of the hollow shaft 41 which is located within the cup-shaped housing 39, there is secured a sector 48 in which there is provided an arcuate slot 49 in which a pin 50 is adjustably secured. To the end of the shaft 44 which is located within the cup-shaped housing 39, there is secured the inner end of a bimetallic coil spring 51 whose outer end engages the pin 50 when its temperature is below a predetermined value.

To the shaft 44, between the inner end of the hollow shaft 41 and the wall of the body 18 opposite that through which the hollow shaft extends, there is secured an element 52. The element 52 is a U-shaped piece of sheet metal through whose arms the shaft 44 extends and through whose base which is made of double thickness by folding the sheet metal upon itself extends the screw 53 which secures the element to the shaft 44. On each of the arms of the element 52, there is formed a finger. The finger 54 overlies the finger 43 on the arm 42 and the finger 55 is adapted to engage the abutment 56 to limit movement of the choke valve 15 toward its closed position and to engage the abutment 57 to limit movement of the choke valve toward its open position.

When an engine on which there is installed the mechanism illustrated in the drawing and hereinbefore described is not operating, the choke valve 15 is, unless the temperature of the engine exceeds a predetermined value, held closed by the bimetallic coil spring 51. If, when its temperature is below this predetermined value, the engine is cranked, the choke valve 15 will remain closed or very nearly closed until the engine begins to operate under its own power and, consequently, during this period, the engine will be supplied with the extremely rich combustible mixture which is conducive to quick and easy starting. As soon as the engine begins to operate under its own power, the flow of air past the choke valve 15 will cause it to open partially and the ratio of fuel to air in the combustible mixture supplied to the engine will be decreased. The extent to which the choke valve opens when the engine begins to operate under its own power is dependent upon the speed of the engine and the resistance offered by the bimetallic coil spring 51 which varies inversely with the temperature of the engine, and the combustible mixture supplied to the engine at this time is, although leaner than it was before the engine began to operate under its own power, very rich.

As soon as the engine begins to operate under its own power, withdrawal of air from the interior of the bellows 20 into the intake manifold 11 and, consequently, collapse of the bellows commences. However, because all of the air withdrawn from the bellows must pass through the small opening between the pin 36 and the bore in the valve 34, an appreciable interval of time, e. g., approximately nine (9) seconds, elapses before the bellows is completely collapsed, i. e., until the head 24 of the bellows engages the lower end of the rod 26. As the bellows is collapsed, the rod 25 is raised and the arm 42 and the hollow shaft 41 are rotated in a clockwise direction when viewed as shown in Figures 1 and 2. This rotation of the hollow shaft 41 causes the sector 48 and the pin 50 to rotate in the direction in which they are urged when the choke valve 15 moves toward its open position. Because the flow of

air past the choke valve 15 and the weight of the linkage 45-46-47 tends to move the choke valve toward its open position, this movement of the pin 50 results in further movement of the choke valve toward its open position and effects a reduction in the richness of the combustible mixture supplied to the engine without any change in the temperature of the engine.

When the head of the bellows 20 approaches the upper limit of its movement, the rotation of the arm 42 brings the finger 43 into engagement with the finger 54 on the element 52. After the finger 43 engages the finger 54, further upward movement of the head of the bellows is positively transmitted to the shaft 44 and, therefrom, through the arm 45, the rod 46 and the arm 47, to the choke valve 15, with the result that by the time that the bellows has been completely collapsed, the choke valve will have been positively opened to a predetermined position. Preferably, the position to which the choke valve is opened by the mechanism under consideration is that at which the engine will be supplied with a combustible mixture of such richness that the engine will idle properly while it is cold. Obviously, as long as the engine is idling normally, the choke valve will not be closed beyond this position.

What has been said in the next preceding paragraph is, of course, based on the assumption that the choke valve 15 has not, before the finger 43 reaches the upper limit of its movement, been opened to such an extent that the finger 54 has been moved beyond the upper limit of the path of the finger 43. Of course, if by the time that the head of the bellows reaches the upper limit of its movement, the choke valve has been opened to this extent, it is not desirable that the described action occur and it will not occur.

Because of its proximity to the exhaust manifold 31, the bimetallic coil spring 51 becomes heated during operation of the engine. Increase in the temperature of the bimetallic coil spring 51 causes the end thereof which engages the pin 50 to exert increasingly less pressure thereon and, consequently, as the temperature of the engine increases, the bimetallic coil spring offers less and less resistance to movement of the choke valve 15 toward its open position. Therefore, the increase in the temperature of the engine which results from its operation will cause a gradual decrease in the richness of the combustible mixture supplied to the engine from the time the engine begins to operate under its own power until its temperature reaches a predetermined value when it becomes capable of operating properly upon the combustible mixture with which the carburetor 10 is designed to supply it. When the temperature of the engine reaches this predetermined value, the outer end of the bimetallic coil spring 51 becomes disengaged from the pin 50 and, thereafter, the bimetallic coil spring offers no resistance to the movement of the choke valve toward its open position. Because movement of the outer end of the bimetallic coil spring 51 in response to increase in temperature is not opposed by any externally applied forces, the bimetallic coil spring will not be injured even if it becomes heated to an excessively high temperature.

When the pressure within the intake manifold 11 increases, the valve 34 will move off its seat against the resistance of the spring 35 and gases from the intake manifold will rush thereby into the interior of the bellows 20 and cause it to expand. To prevent these gases carrying into

the upper end of the bore 28 any particles of foreign matter which might get into and clog the small opening between the pin 36 and the bore in the valve 34, a disc 58 of fine screen wire is secured in the recess 30 in the plug-like element 29. If the temperature of the engine is below a predetermined value, expansion of the bellows will, of course, through the linkage which connects its head 24 to the choke valve 15, cause the choke valve to move toward its closed position. Consequently, if, when the temperature of the engine is below a predetermined value, the throttle valve 12 is moved toward its open position or the engine tends to stall, there will be a momentary increase in the richness of the combustible mixture supplied to the engine which will insure smooth and rapid acceleration or prevent stalling of the engine.

Obviously, the mechanism illustrated in the drawing and hereinbefore described will not affect the position of the choke valve when the temperature of the engine on which it is installed exceeds a predetermined value.

Since, when the engine stops, the pressure within the intake manifold 11 rises and the bellows 20 consequently expands and, when the temperature of the engine falls, the free end of the bimetallic coil spring 51 moves toward the pin 50, it is apparent that, whenever the engine stops, the parts of the mechanism illustrated in the drawing and hereinbefore described automatically move to the positions in which they should be when the engine is cranked to start it.

Of course, although we have shown and described the mechanism to which this invention relates mounted on the intake manifold of an engine with the bimetallic coil spring 51 located in juxtaposition to the exhaust manifold thereof, it will be understood that the mechanism may be mounted elsewhere on the engine and that the bimetallic coil spring may be located in juxtaposition to any other heated part of the engine.

We claim:

1. In an internal combustion engine, a carburetor in which there is incorporated a choke valve, a passage through which combustible mixture is conducted from the carburetor to the engine, an element which is movable in response to variations in the pressure within the mentioned passage and is so arranged that its movement in response to a decrease in the pressure within the mentioned passage tends to result in movement of the choke valve toward its open position, a yielding thermosensitive element operatively interposed between the first-mentioned element and the choke valve, and means for positively transmitting movement of the first-mentioned element to the choke valve so that the choke valve will be positively opened to a position at which the engine will be supplied with a combustible mixture of such richness that it will idle properly when it is cold by the time the first-mentioned element reaches the limit of its movement in the direction in which it tends to move in response to a decrease in pressure within the mentioned passage.

2. In an internal combustion engine, a carburetor in which there is incorporated a choke valve, a passage through which combustible mixture is conducted from the carburetor to the engine, an element which is movable in response to variations in the pressure within the passage, a hollow shaft, means whereby movement of the element is positively transmitted to the hollow shaft, a shaft journaled in the hollow shaft,

means whereby movement of the second-mentioned shaft is positively transmitted to the choke valve, a yielding thermosensitive element operatively connecting the mentioned shafts, and means on the second-mentioned shaft adapted to be engaged by the first-mentioned means after it has moved a predetermined distance in the direction in which it tends to move in response to a decrease in the pressure within the mentioned passage to transmit positively further movement thereof in this direction to the second-mentioned shaft so that the choke valve will be positively opened to a position at which the engine will be supplied with a combustible mixture of such richness that it will idle properly when it is cold by the time that the first-mentioned element reaches the limit of its movement in the direction in which it tends to move in response to a decrease in the pressure within the mentioned passage.

3. In an internal combustion engine, a carburetor in which there is incorporated a choke valve, a passage through which combustible mixture is conducted from the carburetor to the engine, an element which is movable in response to variations in the pressure within the mentioned passage and is so arranged that its movement in response to a decrease in the pressure within the mentioned passage tends to result in but does not initially positively produce movement of the choke valve toward its open position, and means for positively transmitting movement of the first-mentioned element to the choke valve so that the choke valve will be positively opened to a position at which the engine will be supplied with a combustible mixture of such richness that it will idle properly when it is cold by the time the first-mentioned element reaches the limit of its movement in the direction in which it tends to move in response to a decrease in the pressure within the mentioned passage.

4. In an internal combustion engine, a carburetor in which there is incorporated a choke valve, a passage through which combustible mixture is conducted from the carburetor to the engine, an element which is movable in response to variations in the pressure within the passage, a hollow shaft, means whereby movement of the element is positively transmitted to the hollow shaft, a shaft journaled in the hollow shaft, means whereby movement of the second-mentioned shaft is positively transmitted to the choke valve, the mentioned shafts being so arranged that movement of the element in response to a decrease in the pressure within the mentioned passage tends to result in but does not initially positively produce movement of the choke valve toward its open position, and means on the second-mentioned shaft adapted to be engaged by the first-mentioned means after it has moved a predetermined distance in the direction in which it tends to move in response to a decrease in the pressure within the mentioned passage to transmit positively further movement thereof in this direction to the second-mentioned shaft so that the choke valve will be positively opened to a position at which the engine will be supplied with a combustible mixture of such richness that it will idle properly when it is cold by the time that the first-mentioned element reaches the limit of its movement in the direction in which it tends to move in response to a decrease in the pressure within the mentioned passage.

5. In an internal combustion engine, a carburetor in which there is incorporated a choke

- valve, a movable element which is so arranged that its movement in one direction is consonant with movement of the choke valve toward its open position, a spring operatively interposed between the choke valve and the movable element, means for positively transmitting movement of the movable element to the choke valve so that the choke valve will be positively opened to the position at which the engine is supplied with a combustible mixture of such richness that it will idle properly when it is cold by the time that the movable element reaches the limit of its movement in the mentioned direction without interfering with movement of the choke valve toward its open position, and means for preventing movement of the choke valve beyond its second mentioned position by the first mentioned means.
6. In an internal combustion engine, a carburetor in which there is incorporated a choke valve, a movable element which is designed to occupy one position when the engine is not operating and another position when the engine is operating normally under its own power, means for positively transmitting movement of the movable element to the choke valve so that the choke valve will be positively opened to the position at which the engine is supplied with a combustible mixture of such richness that it will idle properly when it is cold by the time the engine reaches the last mentioned position without interfering with movement of the choke valve toward its open position, and means for preventing movement of the choke valve beyond its first mentioned position by the first mentioned means.
7. In an internal combustion engine, a carburetor in which there is incorporated a choke valve, a movable element which is designed to occupy one position when the engine is not operating and another position when the engine is operating normally under its own power so arranged that it does not interfere with movement of the choke valve toward its open position but in moving from the first to the last mentioned position may positively open the choke valve to the

position at which the engine is supplied with a combustible mixture of such richness that it will idle properly when it is cold by the time the movable element reaches the last mentioned position, means for preventing positive movement of the choke valve beyond its second mentioned position by the movable element, and a thermally actuated element operatively interposed between the movable element and the choke valve.

8. In an internal combustion engine, a carburetor in which there is incorporated a choke valve, an engine actuated element which is automatically movable from one position when the engine is not operating to another position when the engine is operating normally under its own power, means for positively transmitting movement of the engine actuated element to the choke valve so that the choke valve will be positively opened to the position at which the engine is supplied with a combustible mixture of such richness that it will idle properly when it is cold by the time the engine actuated element reaches the last mentioned position without interfering with movement of the choke valve toward its open position.

9. In an internal combustion engine, a carburetor in which there is incorporated a choke valve, an engine actuated element which is automatically movable from one position when the engine is not operating to another position when the engine is operating normally under its own power so arranged that it does not interfere with movement of the choke valve toward its open position but in moving from the first to the last mentioned position may positively open the choke valve to the position at which the engine is supplied with a combustible mixture of such richness that it will idle properly when it is cold by the time the engine actuated element reaches the last mentioned position, and a thermally actuated element operatively interposed between the engine actuated element and the choke valve.
